UNITED STATES PATENT OFFICE.

EDWARD C. MODES, OF CICERO, INDIANA.

DESIGN FOR A BOTTLE.

SPECIFICATION forming part of Design No. 28,635, dated May 17, 1898.

Application filed April 13, 1898. Serial No. 677,499. Term of patent 14 years.

To all whom it may concern:

Be it known that I, EDWARD C. MODES, a citizen of the United States, residing at Cicero, in the county of Hamilton and State of Indiana, have invented and produced a new and original Design for Bottles, of which the following is a specification, reference being had therein to the accompanying drawings, in which—

- 10 Figure 1 is a side elevation of the bottle. Fig. 2 is an oblique elevation turned at an angle of forty-five degrees from Fig. 1. Fig. 3 is a plan view.
- 15 A is the body portion, which has the four convex surfaces B, C, D, and E, connected by the rounded corners F and producing the centrally-bulging oblong form.

G is a round neck, which in vertical cross-section curves inwardly toward the center and unites with the body portion by a double or substantially ogee curve. 20

The leading feature of my design is the centrally-bulging oblong body and inwardly-curved neck.

What I claim as my invention is— 25

The design for a bottle substantially as herein shown and described.

In testimony whereof I affix my signature in presence of two witnesses.

EDWARD C. MODES.
